HOMOGENIZER

William Spencer Bowen, Westfield, N. J.

Application May 1, 1936, Serial No. 77,310

6 Claims. (Cl. 99—266)

The present invention relates to homogenizing apparatus and embodies, more specifically, an improved form of homogenizer by means of which homogenizing operations may be carried out more effectively than in existing devices. It is known, in the art, to provide rotatable devices into which a substance to be homogenized is introduced axially and directed outwardly by the device due to the centrifugal force set up by reason of its rotation. It is upon devices of this character that the present invention is an improvement and an object of the invention, accordingly, is to provide a homogenizing head or a rotatable device by means of which the substance to be homogenized is repeatedly subjected to impact and shearing stresses in such fashion as to insure the effective and uniform treatment of all portions of the substance passing therethrough.

A further object of the invention is to provide a device of the above character wherein the rotatable member by means of which homogenization is effected is provided with a series of surfaces which lie substantially in planes perpendicular to radii of the head, the surfaces being arranged in staggered relation to subject the substance to repeated impact and shearing stresses.

A further object of the invention is to provide, in combination with a device of the above character, means to supply substance to be homogenized to the device in a simple and effective manner. In this connection, the invention further contemplates the provision of a feed mechanism by means of which a plurality of substances may be introduced into the homogenizing head in a desired fashion.

A further object of the invention is to provide an improved driving and lubricating mechanism by means of which the homogenizing head may be rotated at high speeds without subjecting the driving mechanism to damage, the lubrication mechanism being simple in construction and effective in operation.

A further object of the invention is to provide, in combination with a lubricating mechanism of the above character, structure by means of which the lubricant is effectively supplied to the rotating surfaces by a positive action set up by the rotation of a driving element.

Further objects, not specified above, will be apparent as the invention is described in further detail in connection with the accompanying drawings, wherein

Figure 1 is a view in end elevation, partly in vertical section, taken on a plane passing through the axis of the homogenizing device, showing a

homogenizer constructed in accordance with the present invention;

Figure 2 is an enlarged partial plan view of the lower portion of the homogenizing head shown in Figure 1; and

Figure 3 is a view in section, taken on the line 3—3 of Figure 2, and looking in the direction of the arrows.

With reference to the above drawings, the homogenizing device is shown as being formed with a casing 10 in which a chamber 11 is formed by means of suitable chamber walls 12. The chamber walls 12 terminate in a horizontal upper extremity 13 to which a cover 14 may be secured as, for instance, by means of threads 15. The cover may be sealed to the casing 12 by means of a seal 16, if desired, and coaxially of the cover 14 and upper extremity 13 of the casing 12 there is mounted an homogenizing head 17. This head is supported by a housing 18 which may be formed integral with the casing 12, the housing 18 being formed with an axial bore 19 within which a hollow drive shaft 20 is received. The drive shaft 20 is preferably journaled within bushings 21 and 22 which are formed preferably of a porous substance such as bronze and graphite. Bushing 22 is formed with enlarged extremities 23 and 24 in order that the cylindrical surface thereof may be spaced away from the inner surface of the bore 19 within the housing 18, such space being shown at 25. In order that a suitable driving gear may be mounted in driving engagement with respect to the drive shaft 20, the enlarged portion 23 is cut away at 26.

Bushing 21 is formed with an enlargement 27 which is cut away at 28, similar to the adjacent end of bushing 22, and thus spaces the bushing 21 from the adjacent surface of the bore 19 as shown at 29.

The drive shaft 20 is formed with a spiral pinion 30 which is driven by a cooperating gear 31, mounted upon a shaft 32 within a housing 33, preferably formed integral with the casing 10, and enclosed by a suitable cover 34.

At the upper extremity of drive shaft 20, a cylindrical bushing 35 is splined to a reduced portion 36 of the drive shaft. The bushing 35 preferably has a circular flange 37 formed integral therewith to serve as a step bearing for the homogenizing head 17. A lock nut 38 is provided for securing the homogenizing head 17 to the bushing 35 and drive shaft 20, this lock nut having a downwardly and outwardly curving surface 39 to facilitate the feed of substance to the head. In this connection, the lock nut preferably is

formed with a tapered upper extremity 40, on the sides of which one or more vanes 41 are provided to provide a pump action to force substance into the homogenizing head.

5 In order that substance may be fed to the head, the cover 14 is provided with an upwardly extending portion 42 having an upper opening 43 which communicates through a channel 44 with the central portion of the homogenizing head. 10 This channel preferably has a downwardly extending flange 45 which is received within a central opening 46 within a cover 47, secured to the head 17 by means of bolts 48. A further provision for feeding substance to the head is made 15 in the provision of a transverse conduit 49 communicating between oppositely extending openings 50, formed in the sides of the extension 42, the conduit 49 communicating with a downwardly extending axial conduit 51 formed with a housing portion 52 which surrounds the vanes 41, thus enabling the vanes to function effectively 20 to draw substance through the conduits 49 and 51 into the homogenizing head 17. Inasmuch as the surface 39 of the lock nut 38 curves outwardly, the path of movement of the substance introduced through the openings 43 and 50 will be 25 changed effectively from an axial path with respect to the head 17 to a radial path with respect thereto as the substance leaves the curved surface 39.

30 At this point, the substance is subjected effectively to the centrifugal force resulting from the rapid rotation of the head 17 and, under such force, the substance is directed outwardly radially of the head.

35 Such radial motion of the substance causes it to pass between radially extending vanes 53 carried either upon the head 17 or cover 47 (in the construction illustrated, these vanes are formed upon the head 17). These vanes are 40 wedge shaped, as illustrated in Figure 2, and cause the substance to be guided through radial channels 54, between the respective vanes 53. Outwardly of the vanes 53 a circumferential series 45 of vanes 55 are provided, these vanes being formed with surfaces 56 which extend circumferentially of the axis of the head and terminate in sharpened edges 57.

50 The edges 57 of each of the vanes 55 are spaced apart circumferentially a greater distance than the width of the radial channels 54, in order that the surface 56 may have impinged thereon all of the substance passing through the channel 54 with which it is in radial alignment. The vanes 55 thus are spaced by openings 58 through which the substance passes outwardly radially as it moves over the edges 57. In such radial movement, the substance next impacts against a circumferential series of vanes 59 which are in 55 staggered relationship axially and circumferentially with respect to the vanes 55 in order that the substance may impact against the circumferential surfaces 60 thereof as illustrated by the arrows in Figure 2. Inasmuch as the vanes 59 are similar in formation to the vanes 55, further description thereof is unnecessary except to state that they are preferably larger in size than the vanes 55 in order to afford sufficient strength as well as to effectively overlap the circumferential width of the openings 58. In this fashion, effective impact of all substance passing through the openings 58 against the circumferential surfaces of the vanes 59 is insured.

70 After impact with the surfaces 60, the substance passes through circumferential openings

61 between the vanes 59 and impacts against the circumferential surfaces 62 of a circumferential series of vanes 63. Vanes 63 are similar in formation to vanes 59 and 55 but are preferably larger than vanes 59 for the reason above noted. 5

By means of the above construction, the substance will be seen to be directed effectively through the homogenizing head in such fashion as to insure the effective impact of the substance against the vanes of each of the radially spaced 10 series. This impact occurs under extremely great centrifugal force and is followed by the subjecting of the substance to shearing action as it passes over the edges 57 of each of the vanes. As a result, the resulting homogenizing 15 action is very great and effective homogenization is accomplished. Moreover, by means of the above construction, the material which passes through the slots or passages and over the cutting edges is divided or separated and then remixed at the subsequent passageways. This is 20 illustrated by the arrows in Figure 2. Thus, in addition to shear and impact stresses, the material is subjected to separation and remixing alternately.

25 In order that the rotating members may be effectively lubricated, oil is supplied to the housing 10 by means of an oil cup 64. The oil level within the housing is maintained above the lower extremity 65 of the housing 18. This lower extremity of the housing is provided with a hollow bushing 66 which is retained in position by means of a fitting 67, secured in position by means of a nut 68. The lower extremity of bushing 21 is formed with openings 69 which communicate with the space 29 between bushing 21 and housing 18, being supplied with lubricant through apertures 70 formed in the drive shaft 20. By reason of the rotation of the drive shaft 20, lubricant will be drawn upwardly through the 40 hollow central portion thereof and directed outwardly through the openings 70 upon the gear teeth 30. The lubricant will then fall upon the upper portion 27 of the bushing 21 and pass downwardly into the space 29. From this space, 45 the lubricant will pass through the porous bushing 21 and effectively lubricate the drive shaft 20.

50 Additional holes 71 are formed in the upper extremity of the drive shaft 20 in order that lubricant may be directed outwardly against the upper portion of the bushing 22. Such lubricant will permeate the porous bushing 22 and pass downwardly through the space 25 in order to be available as a lubricant to the extended bearing surface of the drive shaft 20 which it will reach by 55 permeation of the porous bushing 22. As a result of the foregoing mechanism, the driving elements are effectively and positively lubricated under the high speeds of rotation to which the drive shaft is subjected.

60 An outlet 72 is provided for the chamber 11, through which the homogenized substance is discharged. Other features common to mechanisms of this character may be incorporated to afford other common advantages known to the art and, 65 while the invention has been described with reference to the specific construction illustrated in the drawings, it is not to be limited, save as defined in the appended claims.

I claim:

70 1. A homogenizing device comprising a housing forming a homogenizing chamber, a homogenizing head having a recess for receiving substance to be homogenized rotatably mounted in the chamber, a cover having axial aperture in 75

alignment with the axial recess, means on the housing to direct a substance into the recess, a circular flange on the housing extending into the aperture and means in said recess and extending into the substance directing means having a curved surface for directing the substance radially of the head.

2. A homogenizing device comprising a rotatable head having a recess centrally thereof to receive a substance to be homogenized, a plurality of vanes extending radially from the central recess and defining passageways of substantially uniform width, a second series of vanes in radial alignment with the channels and defining a second series channels increasing in width outwardly of the head, said second vanes having shearing edges at the entrances of the second channels and a third series of vanes in radial alignment with the second channels and overlapping the edges of the second series of vanes, said third series of vanes being provided with adjacent shearing edges and defining a third series of channels increasing in width outwardly of the head, whereby upon operation of the device, the material to be homogenized is divided into a plurality of streams which are mixed with adjacent streams in the channels between the second and third series of vanes and the material is subjected to the shearing action of the shearing edges of the vanes.

3. The device set forth in claim 2 comprising a member in the recess having a curved surface for changing the direction of the material entering the recess from substantially axially to substantially radially of the head.

4. A homogenizing device comprising a head adapted to be rotated, said head being formed with a recess centrally thereof to receive a substance to be homogenized and being further

formed with a circumferential series of vanes forming channels extending radially of the central recess through which a substance may pass and second circumferential series of vanes in radial alignment with the channels forming surfaces against which substances passing through the said channels impinge and defining a second series of channels therebetween increasing in width outwardly of the head, said second series of vanes having shearing edges at the entrances of said second channels.

5. A homogenizing device comprising a housing forming a homogenizing chamber, a homogenizing head rotatably mounted in the chamber and formed with a cover having an axial aperture and an axial recess to receive a substance to be homogenized, a fitting on the housing extending into the aperture to direct a substance into the recess, means on the head having a curved surface and projecting into the fitting to direct the substance radially of the head and pump vanes on the last named means to draw a substance into the recess from the housing.

6. A homogenizing device comprising a housing forming a homogenizing chamber, a homogenizing head rotatably mounted in the chamber and formed with a cover having an axial aperture and an axial recess to receive a substance to be homogenized and a circular flange on the housing extending into the aperture, a fitting on the housing to direct a substance into the recess and extending into the aperture, means on the head having a curved surface and projecting into the fitting to direct the substance radially of the head, and pump vanes on the last named means to draw a substance into the recess from the housing.

WILLIAM SPENCER BOWEN.
